CLAIM

The ornamental design for a catheter sterilizing cassette, as shown and described.

DESCRIPTION

FIG. 1 is a perspective view of a catheter sterilizing cassette showing our new design;

FIG. 2 is a top plan view thereof, the bottom plan view being a mirror image thereto;

FIG. 3 is a left side elevational view thereof, the right side elevational view being a mirror image thereto;

FIG. 4 is a front elevational view thereof; and,

FIG. 5 is a rear elevational view.
